SCREW STARTER

Steve Matovich, Campbell, Calif.

Application December 18, 1950, Serial No. 201,312

3 Claims. (Cl. 1—47)

1

This invention relates to screw setting instruments and more particularly to improvements in such devices for handling and starting screws into woodwork and the like incident to subsequent driving of the screws into the woodwork. Tools of this kind are most useful to carpenters in setting small screws and the like into woodwork prior to actually driving the screws home with a screw driver.

It is one object of this invention to provide a simple hand tool for receiving and holding a screw rearwardly of a screw centering guide mouth adapted for placement in an aperture which is to receive the screw.

Another object is to provide in a screw starter a guide mouth so constructed as to facilitate insertion and removal of a screw into and from the screw starter in a novel manner.

Another object is to provide in a screw starting tool a novel screw centering mouth configuration for quick loading and discharging of a screw into and from the screw holding barrel of such tool.

These and other objects and advantages will become apparent in the following description in view of the drawings in which:

Fig. 1 is a perspective view of a screw starting tool embodying the present invention.

Fig. 2 is an enlarged longitudinal section of the tool shown in Fig. 1.

Fig. 3 is a section similar to that of Fig. 2 with certain parts thereof in a different position.

Fig. 4 is a fragmentary perspective view of the loading and discharge mouth of the tool shown in Figs. 1, 2 and 3.

Fig. 5 is a fragmentary section comparable to those shown in Figs. 2 and 3 but showing a modification in the structure thereof.

The tool embodying the present invention, generally designated 10 in the drawings, comprises a sleeve-like casing 11 having a plunger 12 arranged therein for guided movement axially thereof. The sleeve casing 11 also houses a compression spring 13 which circumscribes the plunger 12. One end 14 of the spring 13 engages a fixed abutment 15 provided within the casing 11 and the opposite end 16 of spring 13 engages a projection 17 on the plunger 12 for maintaining the fore end 18 of the plunger 12 in retracted position.

As best seen in Figs. 2 and 3 the projection 17 on the plunger comprises an expansion ring or collar 19 which engages a cap 20 secured to the aft end 21 of the sleeve casing 11 by suitable threading or the like. In this manner the aft 55

2

end of the plunger 12 is maintained in extended position relative to the casing. The aft end of the plunger is preferably provided with an enlarged head 22 disposed a distance from the projection 17 determined by the length of stroke desired for the plunger relative to the casing. The head 22 and the projection 17 thus provide means for limiting movement of the plunger 12 between fully retracted position (Fig. 3) and extreme depressed position (Fig. 2).

The aforementioned fixed abutment 15 provided within the casing 11 comprises a removable baffle 23, Figs. 1 and 2, or if desired can be formed as a shoulder 23' afforded by a reduced passage 24 formed in the fore portion 25 of the casing. For all purposes the baffle type abutment 23 is preferred since it enables installation of a plunger of increased or decreased diameter if required for larger or smaller screws, respectively.

The fore end 26 of the plunger 12 has an axial bore 27 threaded to receive a threaded stud 28 formed integrally of a permanent magnet tip 29. This connection 30 between the tip 29 and fore end 26 of the plunger can be accomplished by the shrinkage method or by a press-fit if desired. However, by making the connection 30 in a manner conducive to removability, the magnet tip 29 can be removed and replaced when its magnetic strength is dissipated. Moreover, if a tip of different size or shape is required for different sized or shaped heads of screws, the change can be readily accomplished with the threaded type connection shown.

In connection with the foregoing change of size of magnetic tip the fore portion 25 of the casing must also be changed to provide one of a diameter suitable for the particular size tip 29 required. Consequently, the casing 11 is built in two sections, fore and aft, coupled together as at 31 by inner and outer threading provided on their respective adjoining ends. Thus the coupling 31 provides a mode of securing the baffle type abutment 23 in place with its open center 32 aligned with the axis of the plunger 12.

The fore portion 25 of the casing 11 ahead of the magnetic tip 29 provides a barrel 33 adapted to hold a screw S. The open end of portion 25 is formed to provide a quick loading, screw centering discharge mouth 35. This mouth is configurated to taper toward the axis —A— of the casing, plunger and magnetic tip to receive the shank of a screw for maintaining the shank —S— in substantial axial alignment with the axis —A—. One side wall of the mouth

35 is provided with a shank receiving slot 36 extending lengthwise the barrel 33, i. e. parallel to the axis —A— thereof. The slot 36 terminates in and merges with a head receiving slot 37 formed transversely of the barrel 33. In other words, the head receiving slot 37 extends from above radially into the barrel 33 to form two U shaped slots 37 and 38 in the respective side walls of the barrel with the bight portion of each such U substantially diametrically opposite each other transversely of the cylindrical barrel 33.

From the foregoing and in Fig. 4 it will be seen that a T shaped slot —T— is formed in conjunction with the tapered mouth 35 and that the extreme end 39 of the mouth is formed to provide a trough 40 axially aligned with the barrel 33 and casing 11. As is illustrated in Fig. 4 the T slot affords reception of the enlarged head —H— of the screw —S— as well as the shank —s— thereof. The trough 40 aligns the shank —s— with the barrel 33 so that when the screw is released it will be attracted into the barrel by the magnetic tip 29 on the plunger 12. Thus the tool 10 is loaded and ready to set the screw in the desired position.

Most generally it is desired to set a screw into the apertures in a piece of hardware to be secured in place on a wall, door buck, or some such surface. For purposes of illustration a hinge —h— has been shown in phantom in connection with the perspective view constituting Fig. 1. Each wing —w— of the hinge is provided with apertures —a— which usually are of the countersunk type. For this reason the extreme end 39 of the mouth 35 is ground to provide a beveled or partially frusto-conical surface 41 similar to that of a countersunk type head of a screw. This beveled surface 41 serves to align the barrel 33 properly with the aperture —a—, it being the usual procedure to lay the surface 41 onto the lower rim of an aperture —a— and then raise the barrel and casing into a position perpendicular to the surface about to receive the screw.

The tool casing 11 is held in one hand while the other hand is used to drive the plunger 12 forward preferably by tapping the head 22 of the plunger with a hammer. In connection with the foregoing the casing 11 is stationary, its beveled fore end (surface 41) being seated against the rim around an aperture —a—. Consequently, when the head 22 is forced forward by the blow of a hammer, plunger 12 is moved forward relative to the casing and against the action of the spring 13 between them. The screw —S— which is firmly held by the magnetic tip 29 of the plunger is guided through the trough 40 and into the surface behind the wing —w— axially with respect to the aperture —a—.

In accordance with the foregoing the first few convolutions of threading on the screw shank —s— will be embedded into the surface receiving the screw sufficient to hold the latter securely in place. Now then, to release the screw —S— from the barrel the casing 11 is withdrawn until the transverse slot 37 registers with the head —H— of the screw whereupon the entire tool is dropped, i. e., moved downwardly.

This tool enables a workman to handle and set more screws per minute than is possible by hand. Screws used in securing cupboard hinges and like hardware are small and therefore notoriously difficult to handle, especially when one's fingers are rough and calloused as are those of carpenters. With the present tool the screws are

merely placed into the T slotted mouth 35 of the barrel after which the tool manipulates the screw. Since the tip 29 is magnetized the screw is held in the barrel despite gravity and therefore will not fall from the barrel. However, upon proper placement of the screw into a wooden or like surface the magnetic forces of the tip are overcome and the tool readily withdrawn from the head of the screw. As a matter of fact expansion of the spring 13 causes the plunger 12 to be withdrawn relative to the casing and thus the magnetic tip 29 is separated from the screw embedded in the manner explained.

While the description of a screw starting tool embodying the present invention has been given in specific detail it will be apparent to those skilled in the art that modifications, alterations and/or variations of it can be made without departing from the spirit of my invention. I therefore desire to avail myself of all modifications, alterations and variations as fairly come within the scope of the appended claims.

What I claim as new and desire to protect by Letters Patent is:

1. In a screw starter having a plunger provided with a magnetic tip and guided for movement axially of a housing together with spring means for normally holding said plunger in retracted position with its tip confined within a forward barrel end of said casing; a screw receiving and guiding discharge mouth for said barrel end of said casing comprising a tapered troughlike tip thereon of U shaped cross section, said tip having a T slot formed therein with the stem of the T coinciding with the open side of the U shaped trough and the crosshead of the T cut into the side walls of said tip to a point diametrically across said barrel end of said casing and transversely of the stem of said T slot to thereby receive the enlarged head of a screw and support the shank thereof axially of said barrel incident to attraction of said screw by the magnetic tip of said plunger, and a beveled surface on the extreme fore edge of said tapered tip adapted to conform to and fit concentrically into a countersunk aperture for axially aligning said barrel and plunger therewith.

2. In a screw starter having a plunger provided with a magnetic tip and guided for movement axially of a housing together with spring means for normally holding said plunger in retracted position with its tip confined within a forward barrel end of said casing; a screw receiving and guiding discharge mouth for said barrel end of said casing comprising a tapered trough-like tip thereon of U shaped cross section, said tip having a T slot formed therein with the stem of the T coinciding with the open side of the U shaped trough and the crosshead of the T cut into the side walls of said tip to a point diametrically across said barrel end of said casing and transversely of the stem of said T slot to thereby receive the enlarged head of a screw and support the shank thereof axially of said barrel incident to attraction of said screw by the magnetic tip of said plunger, and a frusto conical surface at the bight side of said U shaped trough conforming to the frusto conical surface bordering a countersunk hole for aligning the shank of a screw axially therewith.

3. In a screw starter having a plunger guided for axial movement through a sleevelike casing and spring means normally maintaining said plunger in retracted position with its magnetic tip confined within the forward barrel portion

of said casing; a screw receiving and guiding means at the open forward end of said barrel portion comprising a tapering end formed on said barrel having a T shaped slot extending radially through one side thereof with the stem of the T shaped slot extending parallel to the axis of said plunger and casing and the crosshead of the T shaped slot extending transversely of said axis to receive the enlarged head of a screw and maintain the shank thereof in axial alignment with said plunger incident to the tip of the latter magnetically attracting said screw, the extreme fore edge of said tapering end of said barrel being beveled to conform to the shape of a countersunk aperture for facilitating placement of said barrel and plunger axially of a countersunk aperture.
